UNITED STATES PATENT OFFICE.

FRANK F. LANDIS, OF WAYNESBOROUGH, PENNSYLVANIA.

PNEUMATIC STACKER.

SPECIFICATION forming part of Letters Patent No. 569,504, dated October 13, 1896.

Application filed February 15, 1896. Serial No. 579,438. (No model.)

To all whom it may concern.

Be it known that I, FRANK F. LANDIS, a citizen of the United States, residing at Waynesborough, in the county of Franklin and State 5 of Pennsylvania, have invented certain new and useful Improvements in Pneumatic Straw-Stackers; and I do hereby declare the following to be a full, clear, and exact description of the invention, such as will enable 10 others skilled in the art to which it appertains to make and use the same.

This invention relates to pneumatic straw-stackers having telescopic discharge-pipes; and it consists in the novel construction and 15 combination of the parts hereinafter fully described and claimed.

In the drawings, Figure 1 is a side view of the telescopic discharge-pipe, showing it pushed in. Fig. 2 is a plan view of the same. 20 Fig. 3 is a side view of the operating mechanism at the lower end of the pipe, drawn to a larger scale and showing the parts in the positions they assume when the slidable pipe is extended. Fig. 4 is a plan view of the 25 mechanism shown in Fig. 3. Figs. 5 and 6 are details.

A is a portion of the casing of a threshing-machine or separator, and A' is the delivery-pipe of a centrifugal discharger of approved 30 construction.

B is a flexible junction-pipe of approved construction, revolvable on the upper end of the delivery-pipe A'.

C is the discharge-pipe, secured to the upper end of the pipe B, and C' is the slidable section of the discharge-pipe, which slides telescopically over the lower pipe-section.

B' is a circular bracket or turn-table secured to the top of the casing A, and b is the 40 cylindrical base of a frame D, which supports the discharge-pipe. The base b is revolvably supported by the bracket B' in any approved manner, as, for instance, by a ball-bearing. The base b has two short uprights or lugs d secured to it or formed integral with it. These 45 uprights d are arranged one on each side of the base and near its front. Brackets d' are secured to or are formed integral with the rear part of the base b, and are adapted to 50 support the winch E, which may be of any approved construction.

D' are tie-bars coupling together the up-

rights d and brackets d', and forming with the said parts and the base b the said frame D, which is revolvable upon the turn-table or 55 bracket B'.

F are two arms having their lower ends pivoted to the uprights d by the pins f. These arms extend forwardly in an upwardly-inclined direction to the axis of the discharge-pipe and are parallel to its sides. These arms are preferably formed of pipes for lightness and strength.

F' is a yoke or bracket coupling together the upper ends of the arms F and extending 60 in semicircular form under the discharge-pipe at the upper end of the non-slidable pipe-section.

G is a ring mounted on the upper part of the junction-pipe B, or which may be mounted 70 on the lower end portion of the discharge-pipe C. Lugs 40 are secured to the pipe B and prevent the ring from sliding longitudinally of the pipe. This ring G is connected to the front end of guide H' by the links 42, as will 75 be presently described, and thus forms a support for the lower part of the pipe C, and it is provided with two lugs g, which are secured to the arms F.

H is a forked bracket having its lower ends 80 pivoted on the pins f, and H' is a curved rope-guide carried by the bracket H and arranged substantially concentric with the pins f.

The guide H' is preferably provided with a 85 bearing 41, which is journaled on the central portion of the bracket H. The front end of the guide H' supports the ring G by the two curved links 42. The upper ends of these links are pivoted to the guide by the pin 43, and their lower ends are pivoted to the ring G, close above the lugs g, by the pins 44.

The rope-guide H' is pivotally supported in order that it may adapt itself to all the various positions of the discharge-pipe and in a 95 manner it could not do if it were rigidly connected with it.

The guide or bar H' is provided with ratchet-teeth h' on its under side, the use of which will be more fully explained hereinafter.

The upper end of the slidable pipe-section C' has a ring I secured to it, and a ring I' is secured to its lower end.

J are two guide-sheaves carried by the yoke

F' at the upper ends of the arms F, and arranged one on each side of the discharge-pipe.

5 J' are two sprocket-wheels or sheaves secured on a shaft j, which is journaled in the upper part of the forked bracket, and j' is a crank-handle for revolving the said shaft.

K are flexible connections arranged one on each side of the discharge-pipe. Each flexible connection is fastened at its lower end to 10 the ring I', and thence passes over the guide-sheave J to the upper side of the sprocket-wheel J', around the said sprocket-wheel, and thence through a hole in a lug i' at the upper part of the ring I' to the ring I, and has its 15 upper end secured to the said ring I. For lightness and convenience the lower part 2 of the flexible connection K, which passes over the sheave J, is preferably formed of a cord or wire rope. Its middle portion 3 is 20 formed of a drive-chain, so that it may engage with the teeth of the sprocket-wheel, and its upper portion 4, which is held in a fixed relation to the pipe C and ring I' by the lug i', is formed of a rod. A hook 5 connects 25 the cord 2 to the chain 3, and a link 6 connects the chain 3 to the rod 4.

The sprocket-wheel is a little above the upper side of the discharge-pipe, and the point of the attachment of the upper end of the 30 flexible connection with the ring I is a little below the upper side of the discharge-pipe, so that the flexible connection is at an angle to the axis of the discharge-pipe. When the 35 flexible pipe-section is fully extended, the parts 3 and 4 of the flexible connection are in a substantially straight line, and the upward-lifting force on the ring I' due to the angularity of the parts 3 and 4 is but little. The lower end of the flexible connection is attached to the ring I' at a point below the bottom of the sheave J. When the 40 flexible pipe-section is fully extended, the part 2 of the flexible connection below the sheave J is at a considerable angle with the axis of the pipe 45 and exerts considerable lifting force upon the lower end of the pipe. When the flexible pipe-section is pushed in, as shown in Fig. 1, the parts 3 and 4 are at an angle to each other and considerable lifting force is exerted on 50 the ring I'. The flexible pipe-section is wholly supported by the flexible connections, and the parts are so proportioned that the weight of the lower end of the flexible section when pushed in will be balanced by the 55 upward-lifting force of the parts 3 and 4 on the ring I' due to their angularity and the tension to which they are subjected by the weight of the pipe. As the flexible pipe-section is extended the tension on the flexible 60 connection increases, and the angularity between the parts 3 and 4 decreases, so that the pipe slides against a substantially uniform and slight resistance.

The angularity of the lower part 2 of the 65 flexible connections is arranged so as to supplement the action of the parts 3 and 4 and balance the weight of the lower part of the

pipe at all points of its travel as accurately as possible.

The slideable pipe-section is moved in or 70 out according to the direction in which the crank-handle j' is turned. Its weight is practically balanced upon the guide-sheaves. Its end thrust is transmitted to the base by the arms F, which are arranged in line with the 75 direction of the thrust, and the friction of the parts holds the slideable pipe stationary until the crank-handle is turned.

The angularity of the whole discharge-pipe is changed by means of the winch E, which 80 is provided with a rope e, attached to the front part of the guide H'. The rope e rests on the rope-guide and is secured to the barrel 10 of the winch. The winch is preferably provided with a worm 11, secured on a shaft 85 12 and provided with a wheel 13 or a handle for operating it. The worm gears into a worm-wheel 14, secured on the barrel, and revolves the barrel. The barrel 10 is journaled on the barrel-shaft 15. 16 is a strong spiral 90 spring having one end secured to the shaft 15 and the other end secured to the barrel. The weight of the discharge-pipe is mainly supported by this spring, so that the teeth of the worm and worm-wheel are relieved of 95 much of the weight of the stacker-pipe. The worm-wheel 14, being secured to the barrel, is also journaled on the shaft 15, which is stationary.

The discharge-pipe is oscillated upon the 100 turn-table by means of a toothed wheel M, connected to the base b. Motion is imparted to the wheel M by any approved driving mechanism. (Not shown in the drawings.) The wheel M is not secured direct to the base, 105 but is journaled upon it, and it rests upon the supporting-lugs m.

M' is a pawl which is pivoted to the base and engages with any one of a series of notches m' in the upper edge of the toothed 110 wheel. The base may be disengaged from the toothed wheel by raising the pawl and may then be turned around by hand. The object of this disengagable connection with the toothed wheel is to simplify the driving 115 mechanism. Supposing the driving mechanism had been oscillating the discharge-pipe through an angle of forty-five degrees on one side of the threshing-machine, the pawl can be raised and the discharge-pipe pulled 120 around to the opposite side of the machine or to any other point of the circle. The pawl can then be dropped into another notch, and the driving mechanism will oscillate the discharge-pipe through the same angle, but 125 in another part of the circle, without having to be adjusted or changed.

O is a revoluble and extensible deflector carried by the slideable section of the discharge-pipe. This deflector is formed of pivoted segments and a short pipe O', and is provided with a spring o, which operates to hold the segments in their extended position, as shown in Fig. 1. A flexible connection or

cord P is provided for bending and revolving the deflector. The ends of this cord are secured to one side of the outer segment by a bracket o'.

5 R R' are two sheaves supported at the side of the pipe O'.

S S' are two sheaves supported at the top of the slideable pipe C'. One portion of the cord P passes from the bracket o' over the sheaves 10 R and S, and the other portion of the cord passes from the bracket o' over the sheaves R' and S'.

The deflector is bent backward by pulling back both portions of the cord P simultaneously, and is revolved by pulling one or the other portion of the cord, according to the direction in which the deflector is desired to revolve.

In order to permit the pipe-section C' to be 20 slid in and out without affecting the adjustment of the deflector, take-up devices are used. A yoke 30 is pivoted to the pins f and extends over the flexible junction-pipe under the rope-guide H'. Lugs 31 project upwardly 25 from the yoke 30 on each side of the rope-guide. Sheave-blocks 32 are pivoted to the lugs 31, and 33 are sheaves journaled in the said blocks. The yoke 30 is provided with a pivoted pawl 34, which engages with the 30 ratchet-teeth h' on the bar or rope-guide H', so that the yoke 30 moves back and forth with the said rope-guide as controlled by the winch.

A bar 40 is connected to the two flexible connections K and extends transversely between them. This bar 40 is preferably connected to the hooks 5 by means of pivoted links 41, so that it is free to move to a slight extent in a direction crosswise of the discharge-pipe. Two sheaves 43 are journaled on pins 44, carried by the bar 40. The middle portion or loop of the flexible connection P passes over the sheaves 43, and its ends pass over the sheaves 33, and thence to the sheaves S S' and deflector, as hereinbefore described.

45 The deflector is bent backward by pulling back the yoke 30 by hand, and thereby pulling simultaneously on both ends of the cord P. The pawl 34 holds the yoke in position when pulled back, and the spring o draws forward the yoke and extends the segments of the deflector when the pawl is released from the ratchet-teeth.

What I claim is—

1. In a pneumatic straw-stacker, the combination, with a delivery-pipe, a discharge-pipe, and a flexible junction-pipe; of a revolvable frame supporting the discharge-pipe and provided with a cylindrical base arranged concentric with the delivery-pipe; a wheel journaled or mounted loosely to revolve on the said base and affording a means for oscillating the said frame, and means for coupling and uncoupling the said wheel and base, substantially as set forth.

65 2. In a pneumatic straw-stacker, the combination, with a delivery-pipe, a discharge-pipe, and a flexible junction-pipe; of a revo-

luble frame supporting the discharge-pipe and provided with a cylindrical base arranged concentric with the delivery-pipe; a wheel 70 journaled or mounted loosely to revolve on the said base, and a pawl pivoted to the said base and engaging with notches in the said wheel, substantially as set forth.

3. In a pneumatic straw-stacker, the combination, with a delivery-pipe, a discharge-pipe, and a flexible junction-pipe; of a supporting-frame, arms pivoted to the said frame, a forked bracket also pivoted to the said frame, means for supporting the upper 75 part of the discharge-pipe and the upper ends of the said arms from the said forked bracket, a supporting-rope attached to the said forked bracket, and a ring supporting the lower part of the discharge-pipe and carried by the said arms in front of the said forked bracket, substantially as set forth.

4. In a pneumatic straw-stacker, the combination, with a delivery-pipe, a discharge-pipe, and a flexible junction-pipe; of a supporting-frame, arms pivoted to the said frame, means for supporting the upper part 80 of the said discharge-pipe and the upper ends of the said arms from the said frame, and a ring 85 mounted on the upper end of the said junction-pipe close to the lower end of the discharge-pipe, and permitting the said discharge-pipe to be detached from the junction-pipe, substantially as set forth.

5. In a pneumatic straw-stacker, the combination, with a supporting-frame, a discharge-pipe, and a forked bracket pivoted to the said frame and operatively connected with the said pipe; of a barrel and means for revolving it carried by the said frame, a flexible 100 connection between the said barrel and forked bracket, and a spring connected to the said barrel and operating to sustain the weight of the discharge-pipe, substantially 105 as set forth.

6. In a pneumatic straw-stacker, the combination, with a supporting-frame, and a discharge-pipe pivotally connected with the said frame; of a winch carried by the said frame and provided with a lifting-rope connected 110 with the said discharge-pipe, and a spring connected to the rope-barrel of the said winch and operating to sustain the weight of the discharge-pipe, substantially as set forth.

7. In a pneumatic straw-stacker, the combination, with a frame, and a discharge-pipe pivotally supported thereby; of a curved rope-guide connected with the said pipe and arranged over the front part of the said frame, a winch carried by the rear part of the 125 frame, and a rope secured to the front end of the said guide, resting on its curved portion, and connected to the said winch, substantially as set forth.

8. In a pneumatic straw-stacker, the combination, with a supporting-frame, of a telescopic discharge-pipe, sheaves J at the sides of the discharge-pipe, wheels J' at the lower end of the discharge-pipe, and supporting de-

5 vices carrying the said pipe, sheaves and wheels, and pivoted to the said frame; of flexible connections secured at one end to the lower part of the slidable pipe-section, passing over the said sheaves and wheels and secured at the other end to the upper part of the said slidable pipe-section, the lower part of the said slidable pipe-section being supported by the upper portions of the said flexible connections, substantially as set forth.

10 9. In a pneumatic straw-stacker, the combination, with a supporting-frame, a telescopic discharge-pipe, sheaves J at the sides of the discharge-pipe, wheels J' above the discharge-pipe at its lower end, and pivoted supporting devices carrying the said pipe, sheaves and wheels, from the said frame; of flexible connections secured at one end to the lower part of the slidable pipe-section, passing over the 15 said sheaves and wheels and secured at the other end to the upper part of the said slid- 20 able pipe-section, the upper and lower end portions of the said flexible connections being inclined in opposite directions with respect 25 to the axis of the discharge-pipe, and the lower part of the said slidable pipe-section being supported by the upper end portions of the said flexible connections, substantially as set forth.

30 10. In a pneumatic straw-stacker, the combination, with a frame, and a telescopic discharge-pipe pivotally supported thereby; of flexible connections K having their upper ends attached to the upper side portions of the slidable pipe-section at its outer end, having their lower ends attached to the lower side portions of the slidable pipe-section at its inner end, and having their intermediate portions operatively supported from the said 35 frame; and means for supporting the inner end of the said slidable pipe-section from the upper portions 4 of the said flexible connections, substantially as set forth.

40 11. In a pneumatic straw-stacker, the combination, with a supporting-frame, a telescopic discharge-pipe, guide-sheaves J at the sides of the discharge-pipe, sprocket-wheels J' at the lower end of the discharge-pipe, and pivoted supporting devices carrying the said pipe, 45 sheaves and wheels from the said frame; of flexible connections comprising cords secured to the lower part of the slidable pipe-section and passing over the said guide-sheaves, drive-chains secured to the said cords and en- 50 gaging with the said sprocket-wheels, and rods connected to the said chains and secured to the upper part of the said slidable pipe-section, the lower part of the said slidable pipe-section being supported on the said rods, 55 substantially as set forth.

60 12. In a pneumatic straw-stacker, the combination, with a supporting-frame, and a telescopic discharge-pipe; of a ring connected with the lower part of the said pipe, a forked bracket pivoted to the said frame and connected with the said ring, forwardly-projecting arms pivoted to the said frame and se-

cured to the said ring, sheaves J supported by the front ends of the said arms at the sides of the discharge-pipe, wheels J' supported by the said forked bracket at the lower end of the discharge-pipe, and flexible connections having their ends secured to the slidable pipe-section and passing over the said sheaves and wheels, substantially as set forth.

70 13. In a pneumatic straw-stacker, the combination, with a telescopic discharge-pipe, and flexible connections attached to the slid- 75 able pipe-section and operating to extend it; of an extensible deflector; guide-sheaves 33 and 43 supported respectively at the lower end of the discharge-pipe and by the said flexible connections, and a cord passing around the said guide-sheaves and operatively connected with the deflector, the guide-sheaves 80 43 being constrained to move in the reverse direction to the slidable pipe and operating to keep the said cord taut, substantially as set forth.

85 14. In a pneumatic straw-stacker, the combination, with a telescopic discharge-pipe, and flexible connections attached to the slid- 90 able pipe-section and operating to extend it; of an extensible deflector; a yoke or lever pivoted at the lower end of the discharge- 95 pipe, sheaves 33 supported from the said yoke, sheaves 43 supported from the said flexible connections, and a cord passing around the said sheaves and operatively connected with the deflector, substantially as set forth.

100 15. In a pneumatic straw-stacker, the combination, with a supporting-frame, a tele- 105 scopic discharge-pipe pivotally supported by the said frame, and a bar or guide H' connected with the inner end portion of the said pipe and moving with the said pipe about its pivotal center; of an extensible deflector at the upper end of the said pipe; flexible connections for extending the slidable pipe-section, a pivoted yoke or lever operating to re- 110 tract the deflector and provided with a catch or pawl engaging with the said bar or guide, guide-sheaves 33 and 43 carried respectively by the said flexible connections and by the said yoke, and a cord passing around the said 115 guide-sheaves and operatively connected with the deflector, substantially as set forth.

120 16. In a pneumatic straw-stacker, the combination, with a telescopic discharge-pipe, and flexible connections attached to the slid- 125 able pipe-section and operating to extend it; of an extensible deflector; guide-sheaves 33 supported at the lower end of the discharge- 130 pipe, a bar extending transversely of the discharge-pipe, pivoted links connecting the said bar to the said flexible connections, guide- 135 sheaves 43 carried by the said bar, and a cord passing around the said guide-sheaves and operatively connected with the deflector, substantially as set forth.

140 17. In a pneumatic straw-stacker, the combination, with a supporting-frame, of a tele- 145 scopic discharge-pipe pivotally supported by the said frame and provided with an extensi-

ble deflector at its upper end, flexible connections for extending the slidable pipe-section, a cord for operating the deflector, take-up mechanism connecting the said cord with the 5 said flexible connections and operating to keep it taut, and lifting mechanism carried by the said frame and connected with the discharge-pipe, whereby the angle of the said pipe may be changed without affecting the 10 adjustment of its slidable pipe-section or of its deflector, substantially as set forth.

18. In a pneumatic straw-stacker, the combination, with a supporting-frame, and a telescopic discharge-pipe pivotally supported by 15 the said frame; of an extensible deflector at the upper end of the said pipe; flexible connections for operating the slidable pipe-section, a support—such as a yoke—pivotally supported by the said frame, guide-sheaves 20 carried by the said flexible connections and support, a cord passing around the said guide-sheaves and operatively connected with the deflector, and catch mechanism connecting the said support with the said pipe, constraining 25 it to move back and forth when the pipe is raised and lowered and permitting it to be moved back and forth independent of the motion of the pipe, substantially as set forth.

19. In a pneumatic straw-stacker, the combination, with a supporting-frame, and a dis- 30

charge-pipe pivotally supported by the said frame; of a forked bracket pivoted to the said frame, connections supporting the upper portion of the said pipe from the said bracket, a rope-guide journaled on the said forked 35 bracket, links pivotally connecting the front end of the said rope-guide with the side portions of the lower part of the discharge-pipe, and a winch carried by the said frame and having its rope attached to the said rope-guide, 40 substantially as set forth.

20. In a pneumatic straw-stacker, the combination, with a supporting-frame, a telescopic discharge-pipe, and a sheave J' supported from the said frame independent of the said 45 pipe; of a connection passing over the said sheave and connected to the outer end portion of the slidable pipe-section, and means for suspending the inner end portion of the 50 said pipe-section from that portion of the said connection extending between the said sheave and the outer end portion of the slid- able pipe-section, substantially as set forth.

In testimony whereof I affix my signature in presence of two witnesses.

FRANK F. LANDIS.
